The ornamental design for a combined dimmer control and wall plate, as shown and described.

DESCRIPTION

FIG. 1 is a front perspective view of a combined dimmer control and wall plate in accordance with the new design, showing a slider control positioned to the left.

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a front perspective view substantially similar to FIG. 1, but showing the slider control positioned to the right; and,

FIG. 9 is a front perspective view substantially similar to FIG. 2, but showing the slider control positioned to the right.

The broken lines shown in FIGS. 1 and 3 to 8 of the drawings are for illustrative purposes only and form no part of the claimed design.
